METHOD FOR MAKING HOLLOW METALLIC CANES

Filed May 21, 1934

UNITED STATES PATENT OFFICE

2,006,429

METHOD FOR MAKING HOLLOW METALLIC CANES

John C. Anderson, Chicago, Ill., assignor to Crowe Name Plate & Manufacturing Co., Chicago, Ill., a corporation of Illinois

Application May 21, 1934, Serial No. 726,721

2 Claims. (Cl. 113—116)

The invention relates to improvements in the method for making hollow metallic canes from sheet material.

An object of the invention is the provision of novel and improved means for accomplishing certain steps in the forming of hollow metallic canes from sheet material which has previously been operated upon to produce desired ornamentation thereon.

10 Another object of the invention is the provision of novel and improved means for forming hollow metallic canes from a blank sheet of metal in an efficient and novel relation for the purpose of conserving material.

15 A further object of the invention is the provision of a hollow metallic cane formed out of blank sheet metal, the surface of which had been provided with the desired ornamentation while still in blank or sheet form.

20 A still further object of the invention is the production of a hollow cane from a blank of sheet metal by a series of steps whereby said cane may be produced along lines convenient for low cost manufacture while at the same time resulting in a product which will be highly attractive in appearance, durable, of light weight, and in all other respects highly desirable for the purpose for which it is designed.

25 With the foregoing and other objects in view, which will appear as the description proceeds, the invention consists in the various steps and the means for accomplishing said steps hereinafter more fully described, illustrated in the accompanying drawing and particularly pointed out in 30 the appended claims, it being understood that various changes in the form, proportion, size and minor details of the method may be made without departing from the spirit or sacrificing any of the advantages of the invention.

35 In the drawing forming a part of this specification, I have indicated the various steps of the method and also a form of apparatus for carrying out the same in which:

40 Figure 1 is a plan view of a sheet of metal upon which has been provided desired ornamentation, said sheet also showing the relation in which the same may be cut to provide hollow canes in an efficient and economical manner without loss of material;

45 Fig. 2 indicates a series of rolls through which a blank may be passed for the purpose of transforming said blank into an open tube;

50 Fig. 3 is a cross sectional view of the blank taken substantially on line 3—3 of Fig. 2;

Fig. 4 is a cross sectional view of the blank taken on line 4—4 of Fig. 2;

Fig. 5 is a cross sectional view of the blank taken substantially on line 5—5 of Fig. 2;

Fig. 6 is a view illustrating one form of handle forming means;

Fig. 7 is an elevational view of the finished cane;

Fig. 8 is a sectional view taken substantially on line 8—8 of Fig. 7; and

Fig. 9 is a sectional view of a fragmentary portion of the cane handle taken substantially on line 9—9 of Fig. 7.

Referring to the drawing more specifically, by characters of reference, the letter A designates a blank of sheet metal of any preferred gauge necessary for the requirements, said sheet being of rectangular shape and may be severed along the lines indicated thereon to produce the blanks from which the canes are formed. As shown in Fig. 1, the individual blanks, designated by the letter B have their edges biased as to length of the sheet of metal from which they are cut so as to produce when rolled into tubular form a hollow tube having the desired taper. Said blanks B are alternately reversed from end to end in the cutting operation.

Before the cutting operation is performed, each of the individual blanks B is provided upon its surface by any suitable method, such, for example, as by etching or the like with the desired ornamentation, said ornamentation being designated by the letters C and D. To produce this ornamentation on the sheet while in flat form is a comparatively simple matter and may be done with a minimum of labor and expense. However, to produce the same ornamentation on a cane already formed would be an expensive operation requiring a great deal of time and skilled labor. It is by reason of the improved method to be hereinafter more fully described that it is possible to produce a cane, substantially the entire surface of which may be suitably ornamented to present various ornamental effects, all this being accomplished at a minimum of cost.

The blank B, which is cut from the sheet A, may be passed through a series of shaping rolls 10, 11 and 12, so that the blank in passing through the entire series of rolls is transformed from a flat strip into an open tapered tube or cylinder. Thus the first set of rolls will impart to the strip B the cross sectional shape shown in Fig. 3; the rolls 11 will impart to said strip the cross sectional shape shown in Fig. 4, and the

last set of rolls 12 will complete the formation of the cylinder or tube, bringing the opposite sides thereof into abutting position as shown at 25 in Fig. 5.

5 It is to be understood that the means or mechanism illustrated in Fig. 2, is merely one of several means that may be employed for performing the operations of transforming the blank B from a flat strip into an open tube or cylinder. Thus 10 the shapes imparted to the strip, illustrated in Figs. 3, 4 and 5, may be accomplished by individual dies, the first of which will impart to the strip the cross sectional shape illustrated in Fig. 3, the second of which will impart to the strip 15 the cross sectional shape shown in Fig. 4, and the last of which may bring about the complete closing of the tube as shown in Fig. 5. In the last two steps it may be necessary to insert 20 a mandrel or rod within the partly formed member, shown in Fig. 4, and the side edges of the strip brought into abutting position enclosed around said mandrel or rod.

After the hollow cylinder has been formed, the larger end thereof may be bent to form the handle 13. One means for bringing about the formation of the handle is illustrated in Fig. 6, in which embodiment there is provided a central roller 14 surrounded by a plurality of driven rollers 15. By imparting rotary movement to the outer rollers 15, the free end of the hollow cylinder or tube 25 may be fed to these rollers to bring about the desired bending of the end of said tube to form the handle 13. A member 16 is provided for holding the body of the tube against movement.

30 After the last operation has been completed, the open ends of the hollow tube may be closed by means of the caps 17 and 18, which caps may be of any suitable material, such, for example, as brass or the like, and which will add to the attractive appearance of the finished article. If desired, suitable ring members 19 and 20 may be arranged along the body of the cane to still further ornament the same, and at the same time tend to reinforce the same.

35 The finished article illustrated in Fig. 7 will be light in weight, durable, and will have substantially the entire surface thereof provided with 40 highly attractive ornamentation, which ornamentation could not be economically or practically produced on a cane with the methods heretofore practiced for the production of articles of this character.

It is believed that my invention and many of its advantages should be readily understood from the foregoing with further description, and should also be manifest that while embodiments 5 of the invention have been shown and described for illustrative purposes, various changes in the shape, size and arrangement of parts may be made without departing from the spirit of the 10 invention or the scope as defined in the appended claims.

What I claim and desire to secure by Letters Patent of the United States is:

1. The method of forming ornamented tapered hollow canes which comprises providing repeated desired ornamentation on skelp of rectangular formation, subdividing the skelp into blanks which are adjacently inverted end to end in the blank by relatively severing them along cutting lines which are biased in an adjacently inclined relation along the length of the skelp, the degree of bias corresponding to the degree of taper desired in the finished cane, subjecting the ornamented blank so made to a series of die pressing operations to form a tubular structure with the edges of the blank in substantial abutment, and then subjecting the larger end of said tubular structure to a bending operation to form a handle. 15

2. The method of forming ornamented tapered hollow canes which comprises providing repeated desired ornamentation on skelp of rectangular formation, subdividing the skelp into blanks which are adjacently inverted end to end in the blank by relatively severing them along cutting lines which are biased in an adjacently inclined relation along the length of the skelp, the degree of bias corresponding to the degree of taper desired in the finished cane, subjecting the ornamented blank so made to a series of die pressing operations to form a tubular structure with the edges of the blank in substantial abutment, and then subjecting the larger end of said tubular structure to a bending operation to form a handle, and then providing closing means in the form of caps for the open ends of the tubular structure for facilitating in retaining the structure in tubular form. 25

JOHN C. ANDERSON.
